LOOM WITH STATIONARY WEFT SUPPLY

Cyril Standen Aspden, Colne, England

Application October 12, 1951, Serial No. 251,002

Claims priority, application Great Britain
October 14, 1950

8 Claims. (Cl. 139—125)

This invention relates to weaving looms with a stationary continuous weft supply at each end thereof from which the weft is taken by means of a weft carrier that is picked to and fro across the shed, and the present invention has for its object to simplify the mechanism by means of which this can be done, construct it in such a manner that it can be easily adapted to existing looms, enable the various operations to be performed by movements and at timings which are familiar in weaving, provide ample time for carrying out each operation with the result that very precise timings and positionings of the various co-operating parts are not called for, enable a high rate of production to be obtained with low installation, operative, and maintenance costs and without any special degree of skill for installation, operation or maintenance.

With a view to attaining these objects, the said invention consists of the means hereinafter fully described and particularly pointed out in the claims, the annexed diagrams and the following description setting forth in detail certain structures embodying the invention.

In the said annexed diagrams:

Fig. 1 is a plan and

Fig. 2 is an end view of the attachment and associated parts of the loom.

Fig. 3 is a view of one end of the weft carrier drawn to a larger scale.

Figs. 4 to 14 are views of part of the loom showing the various operative parts in different operative positions.

Figs. 4, 6, 8, 9, 10, 11 and 13 are plan views, and

Figs. 5, 7, 12 and 14 are elevations corresponding to Figs. 4, 6, 11 and 13 respectively.

A (Fig. 1) indicates a double shot of weft taken from a stationary weft supply at each end of the loom and which may consist of any suitable form of weft package or a number thereof supported in a creel.

The weft is drawn from the weft package at each pick by a weft carrier B, hereinafter referred to as a shuttle, that is formed or provided at each end with a weft catcher B¹, hereinafter referred to as hook. This hook is so shaped that it takes hold of the loop A¹ of the double shot of weft as it is drawn across the shed and permits of its easy removal.

The point of the hook is towards the back of the loom, being inclined somewhat towards the leading tip of the shuttle. This inclination is necessary so that the hook can grasp the weft thread, which is positioned approximately parallel to the selvedge, as the shuttle enters the shed. When the hook of the shuttle has contacted the weft, it draws it into the shed as a double pick looped round the hook, one end of the loop being held at the selvedge, and the outer end being drawn from the weft supply cone situated below the shuttle box.

The weft after being drawn from the weft package is taken through a guide which conveniently consists of a tube C that moves to and fro with the sley D and may be fixed to it.

2

After leaving the tube C the weft is taken through a weft transfer guide E which consists of an eyelet formed in the upper end of a rod E¹ which may be slightly offset as shown in Fig. 2. This rod E¹ is slidable in guides E² (Fig. 2), which are attached to the sley swords D¹ and is pulled downwardly therein by a spring E^x so that its lower end is kept in contact with the front end of a tappet arm E³ that is pivoted at its rear end to a stationary part of the loom frame. The tappet arm E³ is provided with a runner E⁴ that is kept in contact with a tappet E⁵ on a tappet shaft of the loom by a spring E⁶ that is attached to the sley sword D¹. This mechanism causes the weft transfer guide E together with the portion of the weft that passes through it to be moved up and down as and when required.

Situated in proximity to the weft transfer guide E is a horizontal rod F that is slidable in guides F¹ and has a reciprocating endwise movement imparted to it by a connection from a tappet F² on the tappet shaft of the loom.

In the example shown this connection consists of a tappet arm F³ that is pivoted to a stationary part of the loom frame and is formed with or has rigidly connected to it an upwardly extending member F⁴ that is slotted at its upper end for the passage of the rod F on which are fixed two collars F⁵ one at each side of the member F⁴ and which may be bridged by a connecting portion F⁶ (Fig. 1) to prevent the rod F from rotating. With this arrangement the member F⁴ is moved forward by the tappet F² and its return movement is effected by a spring F⁷ that is anchored to any suitable fixture such as F⁸ and keeps the arm F³ in contact with the tappet F². The tappets E⁵ and F² with their attendant parts are duplicated at each side of the loom and operated alternately.

Rotatable on the rod F is a circular brush G the

bristles or equivalents of which face more or less towards the front of the loom and this brush holds a portion of the weft after it has passed through the eyelet E in a position in which it will be caught by the hook B¹ at the trailing end of the shuttle as the latter is picked out of

the box H. Situated between the end of the reed J and the horizontal rod F is the weft engaging strip K with the help of which the weft is held while the hook B¹ frees itself from the weft. In the example shown in Fig. 2 this weft engaging strip consists of a closely coiled spring

opened out for a portion of its length to provide a serrated surface at the point of contact with the weft and within the coil may be a flexible core to prevent the weft from becoming entangled in the coil. This spring K is maintained in a state of tension, for which purpose it

may be hooked on to the two stationary fixtures F⁸ previously referred to, and it extends across a recess D² in the top of the sley D and is taken through a guide eye K³ in a band K⁴ or other flexible connection that is fastened at its lower end to the tappet arm E³ (Fig. 2) and at its upper end by a spring K⁵ to a fixed point of anchorage K⁶.

This arrangement causes the weft engaging strip to be moved up and down as and when required. Instead of the weft engaging strip being made in the form of a spring it may consist of any other form of flexible member such for example as a strap, thread, or wire, as shown in Fig. 1, having a serrated surface which is brought down across the pick of weft at the correct time so as to hold the loop A¹ while the movement of the shuttle B causes the hook B¹ to free itself from loop A¹.

The flexible member makes contact with the upper strand of the loop A¹, and although the continued downward movement of the flexible member does press the strand downwardly to some extent, the main function of the flexible member is to hold the strand. However, it is the subsequent movement of the shuttle by means of which the thread is enabled to be free. The examination of Figs. 4 and 6 reveals that there is movement of the shuttle

70

box (and consequently the shuttle) relative to the fell of the cloth. In Fig. 4 the shuttle is behind the fell whereas as is shown in Fig. 6 it is in front of the fell. This movement is due to the normal beating up action of the sley which carries the shuttle box and it is during this movement that the shuttle frees itself from the loop of weft thread. Once the loop has been disengaged, it falls down away from the spring. Thus the particular degree of inclination of the upper surface of the hook is not particularly important because it is the movement of the shuttle in relation to the fell which releases the loop of weft. It is to be noted however, that due to a necessary slight inclination of the hook towards the leading tip of the shuttle, as the hook disengages itself from the weft loop, a certain slight extension of the loop will occur, which is permissible since one end of the loop is freely connected to the weft supply. If there were no inclination of the point of the hook towards what is the leading tip of the shuttle, then the hook would not pick up the weft while if the inclination were too great, the forward movement of the shuttle in the box would not be able to disengage the hook from the weft loop. Between these two extremes there is a choice of inclinations of the hook. The ends of the strap, thread, or wire K may be attached to adjustable screw hooks K?

A cycle of operations is as follows:

Supposing, for example, that the shuttle B is being taken from the shuttle box at the right hand side of the loom; as it leaves the box the hook B¹ at its trailing end catches the weft between the eyelet E and the rotatable brush G and takes a double shot A or pick of weft to the left hand side of the loom as shown in Figs. 4 and 5. The pick is then beaten up (see Figs. 6 and 7), and during the beat up, the loop A¹ is held by spring K and the shuttle frees itself from loop A¹. The spring K then continues to descend into the recess D² so that the shuttle may pass over it on its way back taking with it a double shot of weft to the right hand end of the loom.

At the same time that this pick is being removed from the shuttle and in the process of being beaten up, the supply end of the weft at the right hand side of the loom is being prepared for the next pick from that side. This is achieved by the eyelet E raising the weft when it has reached a position in front of the brush (Fig. 7). As the sley moves back the weft is held by the brush and since the eyelet E together with the adjacent portion of the weft is in its raised position, the shuttle B as it arrives from the left hand side of the loom passes under the weft (Fig. 9). At the same time that the eyelet E is raising the weft for the shuttle to pass under it, so also is the coiled spring K being raised in readiness for descending and engaging the pick carried by the shuttle. While the shuttle frees itself from pick from the right hand side and the pick is being beaten up, the rod F carrying the brush G at the left hand end is moved forward to keep the brush in front of the shuttle so that they do not come into contact (see Fig. 6), and at the same time ensure that the weft does not get displaced and lodge behind the shuttle which would prevent its being carried across the shuttle race as the shuttle was picked. While the sley is receding, the eyelet E descends and places the weft across the shuttle in readiness for picking. At the same time that the sley is receding, so also is the rod F carrying the brush G at the left hand end receding, but later or slower, than the sley so that the weft is kept tensioned thus facilitating the correct engagement of the shuttle hook with the weft. When the shuttle moves out of the box the hook at its trailing end engages the weft and carries it across the sley (Fig. 9), at the same time the tension on the weft causes the brush to revolve and allows the weft to leave the brush and be carried into the body of the cloth. In Fig. 9 the shuttle has been picked from the left hand end of the loom to the right hand end and the process is then repeated, the various movements described

taking place at the opposite end of the loom to that described with reference to Figs. 4 to 8.

Thus Fig. 9 corresponds for a left to right pick to Fig. 4 for a right to left pick and in a similar manner Figs. 10, 11 and 12 correspond to Figs. 5, 6 and 7 respectively.

Figs. 13 and 14 illustrate a further right to left pick with the shuttle part way across the shed.

This process is repeated alternately from each side and if the weft is drawn from sufficiently large packages at each side, continuity of weaving is obtained from a continuous supply of weft. The loops left at each side of the cloth can either be cut off during weaving or so positioned to avoid entanglement by being brushed or pulled out of the path of the weft supply, or preferably held in the desired position by means of suction. This is effected in the arrangement shown through a suction nozzle L from any suitable form of suction producing apparatus.

By mounting supplies of various kinds or colours of weft for use from one or both sides of the loom and selecting the ones required for insertion in the cloth, any desired weft pattern may be obtained.

The selvedge of the cloth is so woven at each side that the succeeding picks from each side go into a different warp shed. This produces a "fast" selvedge, which will remain so, even if the loops are cut off. A distinct advantage in using a flexible weft engaging means is that in the event of a faulty weft carrier flight, resulting in the shuttle being trapped or being so positioned as to strike the weft engaging strip, no damage results. The shuttle may be made of metal, wood, plastic or any suitable material or combinations of materials.

In adapting the invention to take a single shot of weft across the loom at each pick, the weft would be severed near the cloth selvedge.

Or, alternatively, the weft could be severed and knotted, the knot being effected by a knotting device mounted on the loom and operated to form a knot at the chosen movement of the sley, with the knot being of such a size as to prevent its readily being pulled through the slot in the weft catcher.

What I claim as my invention and desire to secure by Letters Patent in the United States is:

1. In a weaving loom adapted to carry a continuous stationary weft supply and having a weft carrier and means to move said weft carrier from an initial position near one side of said loom to a final position near the other side of said loom during each cycle of motion of said loom, the provision of a sley, a weft guide fixed relatively to but movable with said sley, a weft transfer guide movable with said sley and movable upwardly and downwardly in timed relationship with said weft carrier during said cycle, a weft holder adapted to hold said weft in position in the path which said weft carrier is adapted to follow, said weft holder being movable horizontally in timed relationship with said weft carrier during said cycle, a weft catcher means carried by said weft carrier to catch hold of the weft at the commencement of said cycle and to disengage itself from the weft at the end of said cycle and a weft engaging means for engaging said weft to prevent movement thereof with said weft catcher means while the latter disengages itself at the end of said cycle.

2. In a weaving loom adapted to carry a continuous stationary weft supply and having a weft carrier and means to move said weft carrier from an initial position near one side of said loom to a final position near the other side of said loom during each cycle of motion of said loom, the provision of a sley, a weft guide fixed relatively to but movable with said sley, a weft transfer guide movable with said sley and movable upwardly and downwardly in timed relationship with said weft carrier during said cycle, a weft holder in the form of a brush adapted to hold said weft in position in the path which said weft carrier is adapted to follow, said weft holder being also adapted to move horizontally towards and away from the front of said loom in timed relationship

with said weft carrier during said cycle, a weft catcher carried by said weft carrier and adapted to catch hold of the weft at the commencement of said cycle and to disengage itself from the weft at the end of said cycle and a weft engaging means for engaging said weft to prevent movement thereof with said weft catcher means while the latter disengages itself at the end of said cycle.

3. In a weaving loom adapted to carry a continuous stationary weft supply and having a weft carrier and means to move said weft carrier from an initial position near one side of said loom to a final position near the other side of said loom during each cycle of motion of said loom, the provision of a sley, a weft guide fixed relatively to but movable with said sley, a weft transfer guide movable with said sley and movable upwardly and downwardly in timed relationship with said weft carrier during said cycle, a weft holder adapted to hold said weft in position in the path which said weft carrier is adapted to follow, said weft holder being also adapted to move horizontally towards and away from the front of said loom in timed relationship with said weft carrier during said cycle, said weft holder comprising a substantially horizontal rod extending from the rear part of said loom to the front part of said loom and a rotatable brush carried by said rod with the bristles of said brush extending towards the front of said loom, said brush being adjacent to said weft transfer guide when said sley is substantially in its forward position and being adapted to hold a portion of weft extending from said transfer guide to previously woven fabric in said loom and also being adapted to be rotated through the tension of the weft caused by said movement of said weft carrier, such rotation allowing the weft to be released from said bristles, a weft catcher carried by said weft carrier and adapted to catch hold of the weft at the commencement of said cycle and to disengage itself from the weft at the end of said cycle and a weft engaging means for engaging said weft to prevent movement thereof with said weft catcher means while the latter disengages itself at the end of said cycle.

4. In a weaving loom adapted to carry a continuous stationary weft supply and having a weft carrier and means to move said weft carrier from an initial position near one side of the said loom to a final position near the other side of said loom during each cycle of motion of said loom, the provision of a sley, a weft transfer guide movable with said sley and movable upwardly and downwardly in timed relationship with said weft carrier during said cycle, a weft holder adapted to hold said weft in position in the path which said weft carrier is adapted to follow said weft holder being also adapted to move horizontally towards and away from the front of said loom in timed relationship with said weft carrier during said cycle, said weft holder being movable horizontally in timed relationship with said weft carrier during said cycle, a hook on said weft carrier adapted to catch the weft at the trailing end of said carrier at the commencement of said cycle and to disengage itself from the weft at the end of said cycle and a weft engaging means for engaging said weft to prevent movement thereof with said hook while the latter disengages itself at the end of said cycle.

5. In a weaving loom adapted to carry a continuous stationary weft supply and having a weft carrier and means to move said weft carrier from an initial position near one side of said loom to a final position near the other side of said loom during each cycle of motion of said loom, the provision of a sley, a hook on said weft carrier adapted to catch the weft at the trailing end of said weft carrier at the commencement of said cycle and to disengage itself from the weft at the end of said cycle and weft controlling means adapted to operate in predetermined time relationship at each side of said loom, each of said weft controlling means comprising a weft guide fixed relatively to but movable with said sley, a weft transfer guide movable with said sley, means to raise said weft transfer guide when the sley is substantially in its forward position, means to lower said weft transfer guide during the remainder of said cycle, a substantially horizontal rod extending from the rear part of said loom to the front part of said loom, a rotatable brush carried by said rod with the bristles of said brush extending towards the front of said loom, said brush being adjacent to said weft transfer guide when said sley is substantially in its forward position and being adapted to hold a portion of weft extending from said weft transfer guide to the warp in said loom and also being adapted to be rotated through the tension on the weft caused by said movement of said weft carrier, such rotation allowing the weft to be released from said bristles, means to move said brush towards the front of said loom during said movement of said weft carrier, a flexible weft engaging strip, means for raising said strip prior to said weft carrier moving into said final position in said cycle, means for lowering said strip into engagement with the weft in order to engage the weft adjacent said hook at said trailing end of said weft carrier to prevent movement of said weft with said hook while the latter disengages itself at the end of said cycle.

6. In a loom as claimed in claim 5 the provision of a flexible weft-engaging strip having a serrated surface adapted to engage the weft.

7. In a loom as claimed in claim 5 the provision of a flexible weft-engaging strip comprising a coiled spring extended to an extent sufficient to allow the weft to enter between adjacent coils of said spring.

8. In a loom as claimed in claim 5 the provision of suction means near each side of said loom, said suction means being adapted to hold loops, formed at the selvage of the fabric during weaving, from entanglement with said weft-controlling means and from entanglement with subsequent picks of weft.
